(57) **CLAIM**

The ornamental design of an electric motor, as shown and described.

DESCRIPTION

FIG. 1 is a perspective view of an electric motor showing our new design;

FIG. 2 is a left side elevational view of the electric motor of FIG. 1;

FIG. 3 is a right side elevational view of the electric motor of FIG. 1.

FIG. 4 is a top view of the electric motor of FIG. 1; and,

FIG. 5 is a front elevational view of the electric motor of FIG. 1.
